ALBERT RONTKE, OF BRIDGEPORT, CONNECTICUT, ASSIGNOR TO THE SINGER MANUFACTURING COMPANY, A CORPORATION OF NEW JERSEY.

BINDER-HEAD FOR SEWING-MACHINES.

1,150,628.

Specification of Letters Patent. Patented Aug. 17, 1915.

Application filed February 24, 1913. Serial No. 750,132.

To all whom it may concern:

Be it known that I, ALBERT RONTKE, a citizen of the United States, residing at Bridgeport, in the county of Fairfield and State of Connecticut, have invented certain new and useful Improvements in Binder-Heads for Sewing-Machines, of which the following is a specification, reference being had therein to the accompanying drawings.

10 This invention relates to improvements in binding attachments for sewing machines, and has for its object to provide a binder-head capable of adjustment to meet the requirements of slight variations in the width 15 of the binding, and preferably combined with means for giving adjustments to said binder-head in the direction of its length at the will of the operator during the binding operation.

20 Referring to the drawings, Figure 1 is a plan view of the improved attachment, together with a portion of a sewing machine cloth or bed plate, Figs. 2 and 3 front and rear end elevations, respectively, of Fig. 1, 25 Fig. 4 a detail view, in perspective, of the braid-guiding member and its carrier, and Fig. 5 a longitudinal central section of the braid-guiding member and braid-guiding element, together with a full-line view of 30 the braid-guide carrier.

Referring to the figures, 1 represents a portion of a sewing machine cloth or bed-plate, 2 the attachment base-plate secured by screws, as 3, to said bed-plate, 4 the braid-guide carrier provided with a braid-guiding member 5, said carrier being slidably mounted on said base-plate and guided in its oppositely-directed movements by the guide 6, forming a part of said carrier, 35 tracking the guideway 7 formed in the base-plate 2, the braid-guiding member 5 being provided at its delivery end with a concave braid-guide 8 and inclined guiding walls, as 9, and for a portion of its length with edge-guiding walls, as 10. The carrier 4 is slidably secured upon the base-plate 2 by adjusting lever 11, spring washer 12, and screw 13, the latter passing through the slot 14 formed in said carrier and being threaded 40 into said base-plate, said adjusting lever acting, through the pin 15 secured in said carrier entering the opening 16 of greater diameter (shown in dotted lines only, Fig. 1) formed in said lever, to give adjustments

to the binder-head in the direction of its 55 length.

17 represents a braid-guiding element pivoted by pin 18 on the braid-guiding member 5, the forward end of said braid-guiding element being provided with inclines, as 59 19, and edge-guides, as 20, and its opposite end with an adjusting screw 21 which acts against the wall 22 of said braid-guiding member to rock the element 17 on the pin 18 in opposition to the resiliency of the 65 spring 23, which latter is seated at one end on a step 24 forming a part of the braid-guiding member 5, its opposite end contacting with an overhanging bracket 25 forming a part of said braid-guiding element. 70

In the practical use of the binder-head, supposing it to be combined with the means for adjusting it in the direction of its length during the binding operation, the base-plate 2 is secured to the bed-plate so that the concave braid-guide 8 will be in proper relationship with the line of seam formation when the binder-head occupies its central position with respect to its longitudinal adjustments. To effect the threading of the 80 binder-head, the braid is passed from the supply through the opening 26 formed in the convex wall 27 of the braid-guiding member 5 and concave wall 28 of the braid-guiding element 17, and is inverted over the 85 inclines 9, 9, with its folded edge in guiding relationship with the concave braid-guide 8 in a manner common to binder-heads of the present class, when said braid, together with the product being bound, is 90 advanced to the action of the stitch-forming mechanism in a manner common to sewing machines generally.

The object of mounting the binder head adjustable in the direction of its length 95 without interfering with the stitching operation is to better accommodate it to the binding of products varying slightly in thickness, it being an advantage when binding the thicker portions to adjust the concave braid-guide 8 slightly nearer the seam line than when binding the thinner portions of the product. 100

After the machine has been put into operation, if it is found that the braid or binding is slightly narrower than the capacity of the binder-head, the adjusting screw 21 is turned inward or advanced against the step 105

24, thus rocking the braid-guiding element 17 on the pivot 18 in a direction to carry its edge-guiding walls 20, 20, nearer the apex of the guiding walls or inclines 9, 9, of the 5 braid-guiding member 5, which acts to reduce the active guiding surface of the latter, the extent of adjustment of the screw 17 being controlled by the requirements of the binding, it being understood that an adjustment 10 of said screw in the opposite direction will act to slightly increase the capacity of the binder-head.

To better adapt the binder-head for 15 guiding the binding from the supply to its delivery end, the braid-guiding member 5 is provided with the edge-guides 10, 10, which are stationary with respect to the axial adjustment of the edge-guides 20, 20; accordingly, when the latter edge-guides are 20 adjusted to accommodate a slight change in the width of the binding, a like adjustment is effected between the edge-guides 10, 10, and the apex or guiding surface of the bracket 25, it being understood that the convex 25 guiding surfaces arranged in the direction of the length of the binder-head control its capacity, and that the similarly arranged concave surface simply acts to hold the binding against accidental displacement 30 with respect to the edge-guides.

What I desire to secure by Letters Patent is:—

1. In a binder-head of the class described, the combination of a guiding member, a 35 guiding element surrounding and pivotally supported on said member, means for adjusting said member and element relatively to each other, and means for maintaining the same relative capacity in the binder-head at the receiving and delivery ends under all conditions of adjustment.

2. In a binder-head of the class described, the combination of a guiding member, a guiding element surrounding and pivotally 45 supported on said member, means for adjusting said member and element relatively to each other, stationary edge-guides on opposite sides of the receiving end of the binder-head and adjustable edge-guides on 50 the opposite sides of the delivery end, for the purpose described.

3. In a binder-head for sewing machines, the combination with a braid-guiding member provided with a concave braid-guide and 55 edge-guiding walls, and a braid-guiding ele-

ment provided with edge-guiding walls, of means for giving to said braid-guiding element adjustments about an axis arranged transverse to its length.

4. In a binder-head for sewing machines, 60 the combination with a braid-guiding member provided with a concave braid-guide and edge-guiding walls, and a braid-guiding element provided with edge-guiding walls and pivotally mounted on said braid-guiding member, of means for effecting relative adjustment of said braid-guiding member and braid-guiding element.

5. In a binder-head for sewing machines, 70 the combination with a braid-guiding member provided at one end with a concave braid-guide and at its opposite end with a step, and a braid-guiding element pivoted on said braid-guiding member and provided at one end with edge-guiding walls and at 75 the opposite end with a bracket, of means interposed between said step and bracket for giving to said braid-guiding element axial movements with respect to said braid-guiding member.

6. In a binder-head for sewing machines, the combination with a braid-guiding member provided at one end with a concave braid-guide and at its opposite end with a step, and a braid-guiding element pivoted 80 on said braid-guiding member and provided at one end with edge-guiding walls and at the opposite end with a bracket and an adjusting screw, of means interposed between said step and bracket for holding said 85 adjusting screw in engagement with said braid-guiding member.

7. In a binder-head for sewing machines, the combination with a braid-guiding member provided with a concave braid-guide, 90 and a braid-guiding element pivoted on said braid-guiding member and provided with edge-guiding walls, of means including a spring acting in opposition to an adjusting screw for effecting relative adjustment 95 of said braid-guiding member and braid-guiding element.

In testimony whereof, I have signed my name to this specification, in the presence of two subscribing witnesses.

ALBERT RONTKE.
